US00D528098S

(12) **United States Design Patent** (10) **Patent No.:** **US D528,098 S**
(45) **Date of Patent:** ** *Sep. 12, 2006

(54) **HOUSING FOR A HANDHELD
COMMUNICATION DEVICE**

(75) Inventors: **Cortez Corley**, Waterloo (CA); **Roman Peter Rak**, Waterloo (CA)

(73) Assignee: **Research in Motion Limited** (CA)

(*) Notice: This patent is subject to a terminal disclaimer.

(**) Term: **14 Years**

(21) Appl. No.: **29/236,798**

(22) Filed: **Aug. 22, 2005**

Related U.S. Application Data

(60) Division of application No. 29/217,476, filed on Nov. 17, 2004, which is a continuation-in-part of application No. 29/205,517, filed on May 17, 2004.

(51) **LOC (8) Cl.** **14-03**

(52) **U.S. Cl.** **D14/138; D14/341**

(58) **Field of Classification Search** D14/137, D14/138, 147-148, 247-248, 144, 390, 391, D14/399, 341-347; 379/433.01-433.13, 379/434, 368; 455/550.1-90.3, 575.3, 566, 455/575.1, 575.4, 575.6, 556.1, 556.2; D21/517, D21/329, 331, 333; 345/169, 168; 400/486; D13/168

See application file for complete search history.

CLAIM

The ornamental design for a housing for a handheld communication device, as shown and described.

DESCRIPTION

FIG. 1 is a perspective view of a housing for a handheld communication device of my new design;

FIG. 2 is a front view thereof;

FIG. 3 is a rear view thereof;

FIG. 4 is a top view thereof;

FIG. 5 is a bottom view thereof.

FIG. 6 is a left side view thereof; and,

FIG. 7 is a right side view thereof.

The broken line showings of FIGS. 1-7 are for illustrative purposes only and form no part of the claimed design.

1 Claim, 5 Drawing Sheets
